Attorney

UNITED STATES PATENT OFFICE.

OLE OLSON, OF RED WING, MINNESOTA.

SEWING-MACHINE ATTACHMENT.

Application filed April 12, 1924. Serial No. 706,120.

To all whom it may concern:

Be it known that I, OLE OLSON, a citizen of the United States, residing at Red Wing, in the county of Goodhue and State of Minnesota, have invented certain new and useful Improvements in Sewing-Machine Attachments, of which the following is a specification.

This invention is a device to be used on sewing machines for the purpose of facilitating and making easy the sewing of cut-outs, tear-drops, and other fanciful holes in leather or other material.

To this end, the invention consists in the provision of a novel gauge or guide by means of which the operator is enabled to lay the seam regularly, evenly, and at a uniform distance from the edge of the cut-out, thereby producing regular and symmetrical work.

In addition to the above, the invention has the further advantageous feature of being so constructed and arranged as to be capable of being moved into or out of operative position so that when in inoperative position, the sewing machine can be used as though the device were not on it.

With the above and other objects in view, the invention also consists in the novel features of construction, arrangement, and combination of parts hereinafter more fully described and explained, and illustrated in the accompanying drawings, wherein:

Figure 1 is a view of the invention as applied to a conventional sewing machine.

Figure 2 is an assembled view of the device, shown apart from the machine, and

The remaining views are detail views.

This invention is primarily intended as an attachment to be used on a Singer sewing machine known as No. 52W7 but it will be readily understood that it may be used on any other similar machine. A sewing machine of conventional type is illustrated in the drawings in which 10 designates the bed-plate of the machine upon which is mounted the arm 11 and supporting post 12. Within the opening 13 in the bed-plate directly below the needle 14 of the machine is placed the throat plate 15 of the attachment. This plate is screwed permanently to the machine and has an opening 16 through which the needle 14 of the machine goes in the usual operation of the machine. Opening 16, as will be noted, is rather close to the slot 17 but a second opening 18 is ar-

ranged further out from the slot as shown. Attached to the machine, below the throat plate 15 is a brace 19 which carries a vertically disposed bearing sleeve 20 in which is mounted for rotation a shaft 21. Secured to the upper threaded end of the shaft, by means of nut 22, is a gauge arm 23 extending horizontally from the shaft but provided with a perpendicular point 24 directly underlying opening 18 of the aforementioned throat plate 15. The shaft 21 is rotated to either the right or left by means of a lever 25 carried at its lower extended end, and a pin 26 on the shaft is arranged to work in slot 27 of the bearing sleeve. Slot 27 has a cam surface 28 upon which the pin 26 is adapted to ride when the lever is moved to the left of the figure so that the shaft is also moved upwardly through the sleeve. The movement is such as to cause the point 24 of the gauge arm to project slightly above opening 18, in which position it is adapted to be used as a gauge or guide by which the sewing of cut-outs or tear-drops is made easy for the operator.

A specimen of work having cut-outs or tear drops is illustrated at 29 and in using the attachment, the work is placed upon the throat plate 15 of the sewing machine so that the point 24 comes within, and bears against the edge of, the cut-out 30 which is to be seamed. The sewing machine is then operated in the usual manner and the work is shifted about as the seam progresses, the point 24 always bearing against the edge of the cut-out and serving as a fulcrum or axis about which the work is shifted. In this way, the seam can be made regularly and at the same distance from the cut-out, or tear-drop, and absolutely parallel with the edge of the same so that the sewing will be uniform and symmetrical.

When it is desired to dispense with the guide, the lever is moved to the right of the figure and a spring 31 forces the shaft down, causing the point 24 to disappear beneath the plate 15 in which event the sewing machine can be used without any effect of the device upon the work.

The invention may be embodied in the sewing machine as a built-in part, or is applied thereon merely as an attachment. It will be understood also that the method of installing and arranging the device upon sewing machines will vary according to the particular style and design of the machine.

and the right is hereby reserved to make all such changes in regard to the construction, proportion, and arrangements of the parts as are proper within the scope of the 5 pended claim.

Having thus described the invention, what I claim as new as desire to secure by Letters Patent, is:—

A guide for a sewing machine, to facilitate 10 the sewing of cut-outs, tear-drops, and other holes of fanciful design, which consists of a bracket arranged beneath the throat-plate of the machine, a shaft journaled in said bracket, a lever for turning said

shaft from the right to the left and vice versa, means for elevating the said shaft when the latter is turned in one direction and for lowering the shaft when turned in the opposite direction, and a gauge arm carried by the said shaft and presenting a guide element adapted to protrude slightly above the said throat-plate when the said shaft is elevated whereby to provide a bearing point or fulcrum for the edge of a cut-out, tear-drop, or other hole in the work.

In testimony whereof I affix my signature.

OLE OLSON.
